(57) **CLAIM**

The ornamental design for an eyewear frame with appliques, as shown and described.

DESCRIPTION

FIG. 1 is a right side elevational view of the eyewear frame with appliques showing my new ornamental surface design; FIG. 2 is a left side elevational view thereof;

FIG. 3 is a front elevational view thereof;

FIG. 4 is a top front perspective view thereof;

FIG. 5 is a bottom plan view thereof; and,

FIG. 6 is a top plan view thereof.

In the drawings, the broken lines depict portions of the eyewear frame with appliques that form no part of the claimed design.
